UNITED STATES PATENT OFFICE.

ALECK HANNAH, OF WARRENPOINT, NEW JERSEY.

GAUZE-LOOM.

No. 899,973.

Specification of Letters Patent. Patented Sept. 29, 1908.

Application filed July 25, 1907. Serial No. 385,593.

To all whom it may concern:

Be it known that I, ALECK HANNAH, a citizen of the United States, residing at Warrenpoint, county of Bergen, and State of New Jersey, have invented certain new and useful Improvements in Gauze-Looms; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates to looms, and more particularly to that class of looms which are designed for weaving gauze or similar fabrics wherein an interlocked weave is employed.

One of the objects of the present invention is to provide new and improved means for crossing neighboring warp threads whereby an interlocked weave is produced.

Other objects will be in part obvious and in part pointed out hereinafter.

The invention accordingly consists in the features of construction, combinations of elements and arrangement of parts which will be exemplified in the construction herein-after set forth, and the scope of the application of which will be indicated in the following claims.

In the accompanying drawings, wherein is illustrated one of the various possible embodiments of my invention,—Figure 1 is a view in side elevation of a loom constructed in accordance therewith; Fig. 2 is a vertical sectional view taken through the loom, looking from the front thereof; Fig. 3 is a plan view showing the needle guard oscillating mechanism; Fig. 4 is a view in elevation upon an enlarged scale of cam mechanism employed for actuating certain operative parts of the loom; Figs. 5 and 6 are elevational views upon enlarged scales, illustrating the positions assumed by the warp threads during the operation of the loom; Figs. 7 and 8 are horizontal sectional views taken through a portion of the loom, illustrating the positions of the parts at successive picks; Fig. 9 is a vertical sectional view taken substantially on the line x—x of Fig. 5; and Fig. 10 is a view on an enlarged scale illustrating the manner of effecting the weave.

Similar reference characters refer to similar parts throughout the several figures of the drawings.

Referring now to the drawings, *a* represents the frame of the loom which carries a crank shaft *b* and a tappet or cam shaft *c*, the driving means for these parts not being shown herein. Warp beams are shown at *v* and *w* respectively which feed body threads 1 and float threads 2. A take-up roll for the woven fabric is shown at *x*, said fabric passing over a glass bar *x'* to said take-up roll, as clearly shown in Fig. 1 of the drawings.

The batten *d* is mounted upon lay-swords *e* fulcrumed as at *f* and is driven by means of a pitman *g* from the crank-shaft *b*. A reed *d'* is mounted upon the batten and the filler or weft *d''* is carried through the sheds by a shuttle *d'''*, as shown in Figs. 7 and 8.

Within the frame *a* of the loom and located behind the rearmost position reached by the batten, is arranged an auxiliary frame *h*, said frame being formed by two vertically disposed parallel bars *i* adjustably secured at their upper extremities to the loom frame by horizontal brackets *k*, the lower ends of said members being adjustably supported in a bracket *m* mounted upon the frame *a*. If desired, the lower ends of the vertical members *i* may be supported from the floor, as by means of a bracket *m'* supported by uprights, as shown in Fig. 2 of the drawings. The vertical members *i* are provided with elongated slots *n*, in which slide the ends *o'* of a vertically reciprocating bar *o*. Bar *o*, in the present instance, is provided with a series of vertically disposed needles *o''* each of which is provided at or near its free end with a suitable eye *o'''* through which extends a float thread 2, a needle being provided for each of the several float threads. To the bar *o* near either end thereof is attached one end of a cord or strip *p*, said strips passing over rollers *p'* suitably mounted upon the loom frame, the opposite ends of said cords being secured to the upper member of a harness shaft *p''*, provided with the usual eyes or mails *p'''* through which the body threads 1 of the warp extend. The lower member of the harness shaft *p''* is connected by means of a cord *p'''* to the lower end of a lever *q* fulcrumed in a bracket *q'* secured to a suitable portion of the loom frame. Lever *q* is adapted to be oscillated at certain intervals, thereby raising bar *o* with needles *o'* and elevating the float threads 2, by means of a double-ended cam *c'* mounted upon the shaft *c*, springs *m''* operating to return the bar *o*, nee-

dles o^2 and float threads 2 to their lower or normal position.

Near the upper ends of members i are arranged trunnions r which carry horizontally disposed, parallel bars r' , said bars being secured together and properly spaced by rods r^2 and r^3 . Mounted upon rods r^2 and suspended freely therefrom and interposed between needles o^2 is a series of substantially 5 U-shaped guards or guides s , the number of guides provided being equal to twice the number of needles and are so arranged with respect to said needles that two adjacent guides will always pass between adjacent needles, as clearly shown in Figs. 2 and 9 of the drawings. Both the body and float threads of the warp pass between the legs of the guide members, as clearly shown in Figs. 7 and 8 of the drawings, the needles o^2 which carry the 10 float threads being disposed intermediate the legs of the guides, and each needle being interposed between two adjacent pairs of guides as above explained.

Depending from bar r^3 is a cord t' which is 25 connected at its lower extremity to the free end of a lever t fulcrumed in the bracket q' and adapted to be oscillated by a substantially heart-shaped cam c^2 mounted upon the shaft c , the free ends of the bars r' being 30 urged to movement in an upward direction by means of retractile springs u . When bars r' are oscillated in the trunnions r , the lower portions or legs of the guides s pass back and forth between the needles o as the 35 latter are raised or depressed, thereby effecting the interlocking of the various threads of the fabric in a manner which will be hereinafter explained.

Having thus described the construction 40 of this embodiment of my invention, the operation thereof may now be understood. When the batten is in a forward position, the needles o^2 with their warp threads 2, which for convenience I have termed "float 45 threads," are in their down or normal position, the harness p^2 being raised, and the mails p^4 have carried their warp threads, which I have termed "body threads," to their uppermost position, and bars r' have 50 oscillated so as to throw the guides s to their forward position, as clearly shown in the full lines of Figs. 1 and 5 of the drawings. As the batten starts on its rearward swing, the needles o^2 begin to rise upon one side of 55 the body threads 1, and, simultaneously with the upward movement of the needles, the harness begins its descent, the needles and harness carrying their respective warp threads with them and past each other 60 until the warp threads assume a position similar to that shown by the dot-and-dash lines in Fig. 5. At the termination of the upward movement of the needles and the downward movement of the harness, the 65 batten guides, needles, and warp threads

will have assumed positions similar to those illustrated in Fig. 7 of the drawings. The shuttle is now thrown to carry the filler d^2 between the sheds formed in the warp threads by the harness and the needles, the 70 batten begins its forward movement, and when it has reached its forward limit of motion, the parts above mentioned will have assumed positions similar to that shown by the full lines in Fig. 6. It will be 75 observed that the needles o^2 have descended and the harness p^2 has risen during the forward movement of the batten, and the guides s have been moved rearwardly until their forward legs are in adjacency with the 80 needles. When the batten again begins to recede or swing rearwardly, needles o^2 begin their upward movement, but in this instance each of the guides has moved the body threads of the warp to such position that 85 each needle will carry its float thread to the other side of its neighboring body thread, said body threads being moved downward as for the previous pick, the parts presently assuming a position similar to that shown 90 in Fig. 8 of the drawings. The shuttle is again thrown and the foregoing operation is repeated indefinitely.

It will be obvious that, since the needles pass their warp threads alternately to either 95 side of the warp threads carried by the harness, a pick being thrown over each time the warp threads have been so crossed, one float thread has been laid partially about a body thread and secured there by the weft and then 100 returned partially about the body thread and similarly secured in such position by the weft. The manner in which the guides s move the body threads so that the needles when rising may alternately pass to either 105 side thereof, whereby the warp threads are crossed, is clearly illustrated in Figs. 7 and 8 of the drawings.

It will be readily seen that weaves different from that above described may be effected by this mechanism. For instance, should a diamond weave be desired, such weave may be produced by crossing the warp threads passing from one dent in the reed d' through the guides s from the left 115 to right, and passing the next warp threads through the next adjacent pair of guides from right to left.

It will accordingly be seen that I have provided mechanism well adapted to attain, 120 among others, all the ends and objects above enumerated, in an exceedingly simple, yet efficient, manner.

The guides which operate to cross the warp threads are preferably made of metal, 125 and therefore will not become easily worn, and the entire operation is accomplished in a positive, economical and thoroughly efficient manner. Another advantage inherent in the construction is that the warp threads 130

being carried between the legs of the guides will be accurately controlled during the weaving operation, enabling the loom to be successfully operated at any desired speed.

5 As many changes could be made in the above construction and many apparently widely different embodiments of this invention could be made without departing from the scope thereof, it is intended that all matter contained in the above description or shown in the accompanying drawings shall be interpreted as illustrative and not in a limiting sense. It is also to be understood that the language used in the following 10 15 claims is intended to cover all of the generic and specific features of the invention herein described and all statements of the scope of the invention which, as a matter of language, might be said to fall therebetween.

20 Having thus described my invention, what I claim and desire to secure by Letters Patent is:

1. In a loom, the combination with the oscillatory batten, of harness for operating 25 one set of warp threads, needles for operating another set of warp threads, and means positioned between said needles for crossing the warp threads of one set over those of the other set.

30 2. In a loom, the combination with the oscillatory batten, of means for carrying one set of warp threads, movably mounted needles for carrying another set of warp threads, and means interposed between adjacent needles for crossing a warp thread of one set over a thread of another set.

35 3. In a loom having the warp threads arranged in a plurality of sets, the combination of needles for carrying the warp threads of one set, and means interposed between said needles adapted alternately to cross the warp threads of one of said sets over the threads of the set carried by the needles.

40 4. In a loom wherein the warp threads are arranged in a plurality of sets, the combination of vertically reciprocating needles adapted to carry the warp threads of one set, and means positioned between said needles adapted to move the warp threads of another 45 of said sets to such positions that during successive upward movements of the needles the warp threads carried thereby will be carried alternately to either side of the warp threads and said second mentioned set.

50 5. In a loom wherein the warp threads are arranged in a plurality of sets, the combination of a plurality of needles for carrying one set of warp threads, and substantially U-shaped guide members located between said 55 needles adapted to cross another set of warp threads over the warp threads carried by the needles.

55 6. In a loom wherein the warp threads are arranged in a plurality of sets, the combination of a plurality of vertically movable needles

dles for carrying one set of warp threads, guide members interposed between adjacent needles through which the warp threads extend, and means for actuating said guides during the vertical movements of said needles, whereby the threads of another set of said warp threads are alternately moved to either side of neighboring threads carried by the needles.

70 7. In a loom, the combination with the frame and the means for advancing the warp threads, the warp being adapted to be maintained in two sets, of a plurality of vertically movable carriers for the warp threads of one set, and means interposed between said carriers adapted to cross the threads of the other of said sets over those carried by said carriers.

75 8. In a loom, having the warp threads arranged in independent sets, needles for carrying the threads of one set and means interposed between said needles for moving the threads of another set past those carried by the needle each time the shed is changed.

80 9. In a loom, having the warp threads divided into body threads and float threads, needles for carrying float threads, and means interposed between the needles for carrying the body threads across the float threads each time the shed is changed.

90 10. In a loom wherein the warp threads are divided into sets of body threads and float threads, of a series of reciprocating needles carrying the float threads, and oscillatory guide members interposed between 95 said needles for crossing the body threads over the float threads each time the shed is changed.

100 11. In a loom wherein the warp threads are divided into body threads and float threads, the combination of a series of vertically movable needles carrying the float threads, harness for carrying the body threads, and oscillatory guide members interposed between 105 said needles and through which the body and float threads extend, adapted alternately to cross the body threads over the float threads simultaneously with the changing of the shed.

110 12. In a loom, the combination with the frame and the means for advancing the warp, the threads of the warp being adapted to be maintained in two sets, of a vertically movable bar, a set of needles mounted upon said bar through which one set of the warp 115 threads extend, and means carried by said bar adapted to cross the threads of the other of said sets over the threads carried by the needles simultaneously with the changing of the shed.

120 13. In a loom, the combination with the frame, means for advancing the warp, and the means for introducing the filler, the threads of the warp being adapted to be maintained in two sets, of a series of verti- 125 130

cally movable needles carrying one set of warp threads, and means interposed between said needles and movable therewith, adapted to move the threads of the other of said sets laterally across the warp threads carried by the needles simultaneously with the changing of the shed.

14. In a loom, the combination with the oscillatory batten, means for advancing the warp, and means for introducing the filler, the threads of the warp being divided into body threads and float threads, of a series of needles, vertically reciprocating means upon which said needles are mounted, the float threads being threaded through said needles and a plurality of substantially U-shaped guide members interposed between adjacent needles, the body threads passing between the legs of said guide members, and means for oscillating said guide members during the reciprocal movements of the needle supporting means.

15. In a loom, the combination with the frame, the reciprocating batten and the warp advancing means, the threads of the warp being arranged in sets of body threads and float threads, of a vertically reciprocating auxiliary frame mounted in the frame of said loom, a series of needles mounted upon said frame and adapted to reciprocate therewith, said needles being adapted to carry the float threads of the warp, and harness for carrying the body threads of the warp, means for moving said auxiliary frame and said harness in opposite directions, whereby sheds may be formed, and oscillatory guide members mounted upon said auxiliary frame and interposed between said needles, adapted to so operate upon said warp threads that the threads of one of said sets are passed across the threads of the other of said sets at the termination of each reciprocal movement of said auxiliary frame.

16. In a loom, the combination with the frame, the batten and the warp-advancing means, the threads of the warp being divided and maintained in two sets, an auxiliary frame mounted to reciprocate vertically in the loom frame, a series of needles upon said auxiliary frame and movable therewith, said needles being adapted to carry one set of warp threads, a harness adapted to carry the other set of warp threads, means for moving said needles and auxiliary frame simultaneously in opposite directions, whereby sheds are formed, and a pair of guide members mounted to oscillate upon said auxiliary frame, said guide members being provided with legs between which the warp threads pass, and means for oscillating said guide members during the reciprocal movements of said auxiliary frame, whereby said guide members coöperate with said warp threads to move the threads of one set across

those of the other set at the termination of each reciprocal movement of said auxiliary frame.

17. In a loom, the combination with the warp-advancing means, the threads of the warp being arranged in two sets, of a vertically movable bar, needles mounted upon said bar, guides oscillating between said needles, said needles being adapted to carry one set of warp threads, a harness carrying the other set of warp threads, and means for oscillating said guides, whereby the threads of one set are passed over those of the other set thereof, during the movements of said bar.

18. In a loom, the combination with the frame and the means for advancing the warp threads, the warp threads being adapted to be maintained in two sets, of a plurality of vertically movable carriers for the warp threads of one set, and means movable in a direction parallel to the direction of advance of the warp threads adapted to cross the threads of one of said sets over those of the other thereof.

19. In a loom, the combination with a frame and the means for advancing the warp threads, the warp threads being adapted to be maintained in two sets, of a plurality of vertically movable carriers for the warp threads of one set, and a plurality of devices which move in a direction parallel to the direction of advance of the warp threads, and through each pair of which one of the warp threads of one of said sets is threaded, adapted to cross the threads of that set over the threads of the other of said sets.

20. In a loom, the combination with a frame and the means for advancing the warp threads, the warp threads being adapted to be maintained in two sets, of a plurality of vertically movable carriers for the warp threads of one set, and a plurality of devices which move in a direction parallel to the direction of advance of the warp threads, and through each pair of which one of the warp threads on one of said sets is threaded, adapted to cross the threads of that set over those carried by said carriers.

21. In a loom, the combination with the frame, an oscillatory batten, and the means for advancing the warp, the threads of the warp being arranged in two sets, of a plurality of vertically reciprocating needles adapted to control the other set thereof, and means movable in a direction parallel to the direction of advance of the warp threads for crossing the threads of one of said sets over those of the other thereof each time the shed is changed.

22. In a loom wherein the warp threads are divided into body threads and float threads, the combination of a series of vertically movable needles carrying the float threads, harness for carrying the body

thread and guide members through which the body and float threads extend, said guide members oscillating in a direction parallel to the direction of advance of the

5 warp threads and adapted to cross the body threads over the float threads simultaneously with the changing of the shed.

In testimony, that I claim the foregoing as my own, I have hereunto set my hand this nineteenth day of July, 1907.

ALECK HANNAH.
